UNITED STATES PATENT OFFICE

2,566,531

PORTABLE HEAD STEAMER

Moses Daniel Nissenbaum, Brooklyn, N. Y., assignor, by direct and mesne assignments, of one-third to Wade M. Wybrants, New York, N. Y., one-third to William Wybrants, Bronxville, N. Y., and one-third to Adel Wybrants, Bronxville, N. Y.

Application January 25, 1947, Serial No. 724,320

2 Claims. (Cl. 4—165)

1

The present invention relates to apparatus for the treatment of the hair and scalp, and more particularly of the type applying steam, hot air or medicated gas.

An object of this invention is to provide a novel and improved apparatus of the character mentioned, which permits the person treated to regulate the flow of steam, air or gas intended for the hair and scalp, in a novel and improved manner.

Another object hereof, is to provide an apparatus of the type described, which is simple in construction, easy and convenient to use, reasonable in cost and efficient in carrying out the purposes for which it is designed.

Other objects and advantages will become apparent as this disclosure proceeds.

In the accompanying drawings, similar characters of reference indicate corresponding parts in all the views; said drawings constituting part of this specification.

Fig. 1 is a perspective view of an embodiment of this invention shown as a removable attachment on a chair.

Fig. 2 shows a person with the hood component of the apparatus over her head and with her head resting on a member controlling a valve.

Fig. 3 is a fragmentary section shown in enlarged scale, showing in particular, the valve and hood portion of the apparatus. Here, when the back of the person's head is pressed against the head rest, steam flow is decreased.

Fig. 4 is similar to Fig. 3, except that the valve structure illustrated accomplishes increase of steam flow with increase of pressure of the head against the head rest.

In the drawings, the numeral 15 designates generally a hood whose rim may be formed with an inward annular trough 16 for the collection of condensate to be drained off through pipe 17, into a receptacle 18 therefor provided. The hood 15 may be mounted on any suitable supporting structure. In the embodiment illustrated, it is shown pivotally mounted atop an uprightly positioned rod 19 which is slidably through a block 20 pivotally carried on a clamp means 21, which is mounted atop the back of a chair 22. Set screw 23 is for positioning rod 19 securely in block 20. The numeral 24 indicates any suitable screw fastening means. It is evident that the hood 15, may be adjusted to be at any desired height above the seat of the chair and tilted as may be required. The drainage receiving receptacle 18 may be carried on rod 19, as well as a steam producer 25, which

2

may be electrically operated or of any other suitable type.

The numeral 26 indicates generally a valve-controlled discharge nozzle means which is mounted on the interior of the hood 15, with its valve-control member 27 terminating in a knob or head rest 28. The discharge orifices 29 may be rearwardly upwardly directed so that steam hits the interior surface of the hood as a guide and deflector therefor. Said valve means may be mounted by a nipple 30 maintained on the hood 15 by means of a lock nut 31. A feed pipe 32 connects said nipple which is the intake port of the valve means 26, with the steam generator 25, or to any other hot-air or gas supply which is the material to treat the hair and scalp with. A compression coil spring 33 is on the shank of the moveable valve-control member 27 between the head rest knob 28 and the casing 20 of the discharge means 26, whereby orifice-control slide 34 is normally at its remote position as shown in Fig. 3, where the discharge orifices are open and in communication with the supply pipe 32. It is evident that pressing the head 25 of the person against the head rest 28, will accomplish gradual closing of the valve. Maintenance of the head at any particular position so that valve member 27 is positioned somewhere intermediate its limit points of travel, will determine the steam flow out of the discharge orifices 29. Here, steam flow increases as the pressure of the head against head rest knob 28, is decreased.

In the embodiment shown in Fig. 4, steam flow increases as pressure of the head against the head rest knob 28 is increased. Here 35 is a duct through the valve slide 34' and all numerals marked prime, are akin to the components of Fig. 3, marked with the same numeral minus the prime.

The manner of use is readily understood from explanation already given and as specifically illustrated in Fig. 2 of the drawings.

This invention is capable of various forms and numerous applications without departing from the essential features herein disclosed. It is therefore intended and desired that the embodiments shown shall be deemed illustrative and not restrictive and that the patent shall cover all patentable novelty herein set forth; reference being had to the following claims rather than to the specific description herein to indicate the scope of this invention.

I claim:

1. In a head steamer of the character de-

scribed, the combination of means including a discharge nozzle adapted to direct a gaseous medium onto the head of a person, a valve having a movable operating member for controlling the flow to said nozzle, spring means adapted to urge said operating member to a predetermined position, a frame supporting said means and valve and a rest member carried on said operating member adapted to be leaned against by the back of the head of the person and when pressed by moving the head backward to move the operating member to adjust the flow to the discharge nozzle.

2. An article as defined in claim 1, wherein the rest member controls valve opening whereby said opening is increased with increase of pressure against said rest member.

MOSES DANIEL NISSENBAUM.
